WHIRLIGIG

Paul Agrillo, Gilroy, Calif.
(P.O. Box 1186, San Jose, Calif.)

Filed Sept. 6, 1960, Ser. No. 62,029

Term of patent 14 years

(Cl. D34—15)

FIG. 1 is a perspective view of a whirligig, showing my new design therefor.

FIG. 2 is an end view of the whirligig as seen from the left in FIG. 1.

FIG. 3 is a top plan view of the whirligig shown in FIGS. 1 and 2; and

FIG. 4 is a side view of FIG. 3.

The cord portions are shown fragmentarily in FIGS. 2, 3 and 4 for convenience of illustration.

I claim:

The ornamental design for a whirligig, as shown and described.
